NASAL AND SINUS IRRIGATOR

Frank E. Brown, Burbank, and George W. Frankel,
Los Angeles, Calif.

Application August 30, 1954, Serial No. 32,063

Term of patent 7 years

(Cl. D83—1)

Figure 1 is a side elevation of a nasal and sinus irrigator illustrating our new design.

Figure 2 is a front elevation thereof.

Figure 3 is a fragmentary perspective view of the irrigator with portions omitted for convenience of illustration.

We claim:

The ornamental design for a nasal and sinus irrigator, substantially as shown.
